UNITED STATES PATENT OFFICE.

WILLIAM L. FRANKS, OF EVANSVILLE, INDIANA, AND WILLIAM O. HASKINS, OF OWENSBORO, KENTUCKY.

MOTOR-CULTIVATOR.

1,174,842.

Specification of Letters Patent. Patented Mar. 7, 1916.

Application filed March 6, 1914. Serial No. 822,962.

To all whom it may concern:

Be it known that we, WILLIAM L. FRANKS and WILLIAM O. HASKINS, citizens of the United States, residing at Evansville and Owensboro, respectively, in the counties of Vanderburg and Daviess, respectively, and States of Indiana and Kentucky, respectively, have invented new and useful Improvements in Motor-Cultivators, of which the following is a specification.

This invention relates to motor cultivators and it consists in the novel features hereinafter described and claimed.

An object of the invention is to provide a motor propelled cultivator with simple and efficient means for adjusting the soil engaging members thereof with relation to each other and also with relation to the frame of the cultivator.

A further object of the invention is to provide means such as indicated which may be manipulated whereby the cultivator may be transformed from a soil stirring implement to a harrow or pulverizer.

With these objects in view the cultivator comprises a frame mounted on wheels. An engine is mounted upon the frame and is operatively connected with the other two supporting wheels of the frame. Beams are pivotally connected with the frame and soil engaging members are pivotally connected with the beams. Lever mechanisms are provided upon the frame and are operatively connected with the soil engaging members to adjust the same and a lever mechanism is mounted upon the frame and is adapted to be used to adjust all of the soil engaging members simultaneously. Other lever mechanisms are mounted upon the frame and may be used for raising and lowering the soil engaging members.

In the accompanying drawings:—Figure 1 is a top plan view of the cultivator; Fig. 2 is a side elevation of the same. The other figures are detailed views of the several features thereof.

The cultivator comprises a frame 1 which includes a front arch axle 2 and a rear arch axle 3. Dirigible wheels 4 are pivotally mounted at the ends of the arch axle 2 and supporting wheels 5 are journaled at the ends of the axle 3. An operator's seat 4' is mounted upon the frame 1 and a steering shaft 5' is journaled in the frame 1. The shaft 5' is provided at its upper end with

a wheel 6 which may be used by one occupying the seat 4' for turning the shaft 5'. Rods or chains 7 are connected with the lower portion of the shaft 5 and the spindles 8 upon which the wheels 4 are journaled. The spindles 8 are pivotally mounted at the ends of the axle 2.

An engine 9, preferably of the hydro-carbon type, is mounted upon the forward portion of the frame 1 and is provided upon its shaft with a sprocket wheel 10. A shaft 11 is journaled for rotation at the forward portion of the frame 1 and carries a sprocket wheel 12. A sprocket chain 13 is trained around the sprocket wheels 10 and 12 and is adapted to transmit rotary movement from the engine 9 to the shaft 11. Sprocket wheels 14 are mounted upon the ends of the shaft 11 and sprocket wheels 15 are fixed to the sides of the wheels 5. Sprocket chains 16 are trained around the wheels 14 and 15 and are adapted to transmit rotary movement from the shaft 11 to the wheels 5 whereby the implement is propelled over the ground.

A shaft 17 is carried at the forward portion of the frame 1 and beams 18 are pivotally connected at their forward ends with the said shaft 17. Spindles 19 are pivotally mounted at the rear ends of the beams 18 and soil engaging members 20 are carried by the said spindles. In the present instance the said soil engaging members 20 are in the form of disks although shovels or points may be substituted for the disks if desired.

A shaft 21 is journaled upon the frame 1 and levers 22 are pivoted upon the shaft 21. Rods 23 pivotally connect the working ends of the levers 22 with the free ends of the spindles 19. Segments 24 are mounted upon the frame 1 adjacent the levers 22 and are provided with teeth. The said levers 22 carry spring pressed pawls 25 which are adapted to engage the teeth of the segment 24 and hold the levers 22 at adjusted positions. A lever 26 is fixed to the shaft 21 and may be used for turning the said shaft and the levers 22 and the segments 24 mounted thereon. A dentate segment 27 is mounted upon the frame 1 adjacent the lever 26 and the said lever 26 is provided with a spring pressed pawl 28 which is adapted to engage the teeth of the segment 27 and hold the lever 26 at an adjusted position.

tion. Levers 29 are mounted upon the rear portion of the frame 1 and are operatively connected by means of rods 30 with a frame 31 which is located below the rear portions 5 of all of the beams 18. By swinging the levers 29 the frame 31 may be raised or lowered whereby the rear portions of the beams 18 may be similarly moved. Therefore it will be seen that means are provided 10 for raising and holding the soil engaging members 20 above the surface of the soil or the said means may be manipulated to lower the said soil engaging members in contact with the soil. By manipulating the levers 22 the soil engaging members 20 may be positioned at a desired angle with relation to the line of draft of the cultivator and by using the said levers independently the said soil engaging members 20 may be 15 adjusted independently of each other. By manipulating the lever 26 all of the soil engaging members 20 may be adjusted simultaneously. The soil engaging members 20 may be disposed parallel with the line of 20

draft of the cultivator or they may be disposed at any desired angle so that they may cast the soil to one side or the other. 25

Having described the invention what is claimed is:—

A cultivator comprising a frame, beams 30 pivotally connected with the frame, spindles pivotally connected with the beams for swinging movement independent of each other, earth working implements carried by the spindles, means for adjusting the spindles upon their pivots independently of each other, and means for adjusting the spindles simultaneously to vary the angle of the earth working implements with relation 35 to the beams. 40

In testimony whereof we affix our signatures in presence of two witnesses.

WILLIAM L. FRANKS.
WILLIAM O. HASKINS.
